STARTING BLOCK

George T. Bresnahan, Iowa City, Iowa

Application February 9, 1938, Serial No. 189,653

5 Claims. (Cl. 272—59)

This invention relates to new and useful improvements in starting blocks used in connection with athletic running tracks.

Among the several objects of my invention are 5 to provide such a block which is extremely simple in construction, which is easily attached to the ground or removed therefrom, which is collapsible and occupies but little space when collapsed, and which embodies a foot supporting plate which is 10 readily adjustable to any one of several positions of inclination.

With these and other objects in view which will 15 more fully appear, the nature of the invention will be more clearly understood by following the description, the appended claims, and the several views illustrated in the accompanying drawing.

In the drawing:—

Figure 1 is a perspective view showing my invention in position for use,

Figure 2 is a perspective view showing my invention collapsed,

Figure 3 is an plan view of the invention, and

Figure 4 is a perspective view of one of the 25 ground-penetrating nails.

Like reference numerals designate corresponding parts throughout the several figures of the drawing.

My invention is formed from sheet metal and 30 comprises a ground-engaging plate A, a foot-supporting plate B, a brace C, and a plurality of ground-penetrating nails D.

The plate A is preferably rectangular in plan view, and is provided adjacent its longitudinal 35 edges with nail openings 5. The plate A is also provided on its rear half with a longitudinal series of centrally disposed stops 6 which are preferably struck upwardly from the plate.

The plate B is hinged as at 7 to the front edge 40 of the plate A and is adapted to be folded either forwardly or rearwardly as shown in Figs. 2 and 3 respectively. Removably attached to the front face of the plate B by bolts 8 is a non-slip facing plate 9 of cardboard or other suitable material.

The brace C comprises an attaching plate 10 45 which is riveted to the plate B and a brace arm 11 which is pivoted as at 12 to said plate 10, the free end of the arm being adapted to engage any one of the stops 6 and thereby retain the foot-supporting plate B at a predetermined angle.

When the device is collapsed, as shown in Figure 2 it will be flat and consequently it will occupy but little space when packed in a suitcase or when packed for shipment. It will be noted that in this collapsed condition the free end

of the brace arm 11 substantially registers with the rear end of the ground-engaging plate A and consequently the package will be no longer than the length of said plate.

Whenever it is desired to attach the block to the ground, the nails D are driven through the openings 5. Each nail includes a shank 13, a head 14, and a flange 15 on the shank disposed in spaced relation to the head for engaging the plate B to limit the downward movement of the nail. 10 Thus the heads 14 will be maintained above the plate A and thereby afford means for readily removing the nails whenever it is desired to take up the block.

It is of course to be understood that the details 15 of structure and arrangement of parts may be variously changed and modified without departing from the spirit and scope of my invention.

I claim:

1. A starting block formed wholly of sheet 20 metal comprising a flat ground-engaging plate, a flat foot-supporting plate hingedly attached at its lower end to the forward end of the ground-engaging plate, a flat brace plate hingedly connected at one end to the rear face of the foot-supporting plate, and a series of stops carried by the ground-engaging plate for cooperation with the free end of the brace to retain the foot-supporting plate at a predetermined inclination.

2. A starting block formed wholly of sheet 25 metal comprising a flat ground-engaging plate, a flat foot-supporting plate hingedly attached at its lower end to the forward end of the ground-engaging plate, a flat brace plate hingedly connected at one end centrally to the rear face of the foot-supporting plate, and a longitudinal series of 30 centrally disposed stops carried by the ground-engaging plate for cooperation with the free end of the brace to retain the foot-supporting plate at a predetermined inclination.

3. A starting block formed wholly of sheet 35 metal comprising a flat ground-engaging plate, a flat foot-supporting plate hingedly attached at its lower end to the forward end of the ground-engaging plate, a flat brace plate hingedly connected at one end to the rear face of the foot-supporting plate, and a series of stops carried by the ground-engaging plate for cooperation with the free end of the brace to retain the foot-supporting plate at a predetermined inclination,

40 the length of the brace being such that when the foot-supporting plate and the brace are folded over the ground-engaging plate the free end of the brace will substantially register with the rear end of the ground-engaging plate.

4. A starting block formed wholly of sheet metal comprising a flat ground-engaging plate, a flat foot-supporting plate hingedly attached at its lower end to the forward end of the ground-engaging plate, a flat brace plate hingedly connected at one end to the rear face of the foot-supporting plate, a series of stops carried by the ground-engaging plate for cooperation with the free end of the brace to retain the foot-supporting plate at a predetermined inclination, and a facing plate removably attached to the front face of the foot-supporting plate.
5. A starting block formed wholly of sheet metal comprising a flat ground-engaging plate, a flat foot-supporting plate hingedly attached at

its lower end to the forward end of the ground-engaging plate, a flat brace plate hingedly connected at one end to the rear face of the foot-supporting plate, and a series of stops struck up from the metal of the ground-engaging plate for cooperation with the free end of the brace to retain the foot-supporting plate at a predetermined inclination, the length of said brace being such that when the foot-supporting plate and the brace are folded over the ground-engaging plate a substantially flat assembly will be presented and the free end of the brace will approximate the rear end of the ground-engaging plate. 5 10 15
